Attorney

UNITED STATES PATENT OFFICE.

CONRAD STEHL, OF OAKLAND, CALIFORNIA.

PENCIL.

1,416,137.

Specification of Letters Patent. Patented May 16, 1922.

Application filed May 16, 1921. Serial No. 470,196.

To all whom it may concern:

Be it known that I, CONRAD STEHL, a citizen of the United States, residing at Oakland, in the county of Alameda and State of California, have invented certain new and useful Improvements in Pencils, of which the following is a specification.

My invention is an improved refillable pencil, simple in construction and operation 10 and cheap to manufacture.

Referring to the annexed drawing in which my invention is illustrated and which forms a part of this specification:

Figure 1 is a side elevation of my pencil. 15 Figure 2 is a longitudinal section of my pencil.

Figure 3 is a longitudinal section of the rotatable sleeve with the slotted side of the lead tube therein shown in elevation.

20 Figure 4 is a side view of the nut for advancing the lead.

Figure 5 is an end view of said nut.

In the drawing 1 indicates a pencil handle formed with a reduced end portion 2 on 25 which fits the upper end of a tube 3. The tube 3 has a partition 4, near its upper end, which engages the end of the reduced portion 2 of the handle and an internal thread 5 is cut in said tube from its lower end 30 nearly up to the partition 4, which thread is engaged by a nut 6. The nut 6 is provided with an axial bore 7 and a lug 8 is formed in the nut extending radially into said bore. The tube 3 is formed with a reduced portion 35 9 extending from its lower end about as far up as the thread 5 to an annular external shoulder 10 on the tube. A rotatable sleeve 11 fits on the reduced portion 9 of tube 3 with its upper end engaging the shoulder 10.

40 A partition 12 extends across the sleeve 11 and engages the lower end of tube 3 while the upper end of the tube engages the shoulder 10. The lower end portion 13 of the sleeve 11 is conical, tapering downwardly.

45 A lead tube 14 extends axially within the sleeve 11 and is secured in the lower end of the sleeve, the partition 12 being provided with a central aperture 15 through which said lead tube extends, whereby said tube is 50 prevented from being bent out of axial relation to the sleeve. The lead tube 14 has a longitudinal slot 16 and extends through the bore 7 of the nut 6 while the lug 8 extends through said slot into the tube against the 55 upper end of the lead 17 in the tube.

The upper end of the tube has a longitudinal slit 18 enlarged at its lower end whereby the upper end of said tube is caused to contract tightly around the reduced portion 2 and hold the tube securely on the pencil 60 handle.

The upper end of the sleeve has a longitudinal slit 19 which is enlarged at its lower end whereby the upper end of the sleeve contracts upon the tube 3 and holds said sleeve 65 on the tube by friction, but allows the sleeve to be turned on the tube.

When the sleeve 11 is turned in one direction the nut 6 and its lug 8 are moved upwardly so that a new lead 17 may be placed 70 in the tube 14. When the sleeve 11 is turned in the opposite direction the nut 6 and its lug 8 are moved downwardly and the lug 8 engaging the upper end of the lead projects its lower end beyond the lower end of the 75 sleeve 11 in position to write.

Having described my invention, I claim:

1. In a refillable pencil, a tube threaded internally upwardly from its lower end, a nut engaging the internal thread of said 80 tube, said nut having an axial bore, a lug on said nut extending into said bore, a sleeve turnably mounted on said tube, a lead tube extending axially within said sleeve and through the bore of said nut 85 and secured in the lower end of said sleeve, said lead tube having a longitudinal slot into which said lug extends above the upper end of the lead in said lead tube, said sleeve being split at its upper end to cause it to engage said first tube with sufficient friction to hold onto said tube.

2. In a refillable pencil, a tube threaded internally from its lower end upwardly and formed with a reduced portion, extending 95 from its lower end, and with an annular external shoulder at the upper end of said reduced portion, a nut in said tube engaging its internal thread, said nut having an axial bore, a lug on said nut extending into its bore, a rotatable sleeve mounted on the reduced portion of said tube with its upper end engaging said annular shoulder, a lead tube in said sleeve secured in the lower end of said sleeve and extending through the bore of said nut, 100 said lead tube being provided with a longitudinal slot into which said lug extends over the upper end of the lead in said lead tube.

In testimony whereof I affix my signature.

CONRAD STEHL.
